UNITED STATES PATENT OFFICE.

HENRY R. SILLMAN, OF BROOKLYN, NEW YORK.

MACHINE FOR MAKING SPOOLS, &c.

SPECIFICATION forming part of Letters Patent No. 253,778, dated February 14, 1882.

Application filed October 31, 1881. (No model.)

To all whom it may concern:

Be it known that I, HENRY R. SILLMAN, of Brooklyn, in the county of Kings and State of New York, have invented certain new and useful Improvements in Machines for Making Spools, Bobbins, and Similar Articles, of which the following is a specification.

My invention relates to machines for making bobbins, spools, bungs, and other small articles of wood, in which the blanks are carried in holders in the periphery of a rotary wheel having a step-by-step or intermittent motion while they are being subjected to the different operations by which they are formed. The rotary wheel is provided with dogs for retaining the blanks in the holders; and the invention consists in the combination, with the wheel, of mechanism whereby the dogs at the proper time are drawn back, first, to permit the insertion of the stick into the holders, and subsequently, to release the bobbins or other articles from the holders.

The invention also consists in the combination, with the rotary wheel and a cutter or cutters, of a pusher shaft or rod adapted to push the bobbins or other articles lengthwise from the wheel, a spindle against which the bobbin or other article is passed, and which is adapted to move longitudinally, like the pusher, to carry the bobbin or other article into a position to be acted on by said cutter or cutters for turning its periphery.

The invention also consists in the combination, with the aforesaid wheel and the pusher shaft or rod and a longitudinally-movable shaft whereby the bobbin or other article is presented to the cutter or cutters for turning its periphery, of the sand or smoothing roll for finishing the bobbins or other articles.

The invention also consists in various combinations of parts, to be hereinafter explained.

In the accompanying drawings, Figure 1 represents a plan of a machine embodying my invention. Fig. 2 represents a vertical section on the dotted line $x x$, Fig. 1. Fig. 3 represents a detail view of a portion of the rotary wheel, a holder thereof, and a dog arranged adjacent to the holder; and Fig. 4 represents a detail sectional view, hereinafter explained.

Similar letters of reference designate corresponding parts in all the figures.

A designates the main wheel which carries the bobbins, and which has notches a , constituting holders formed at equal distances apart in its periphery. The wheel A is mounted on a shaft, A', which is adapted to rotate in suitable bearings in the frame B of the machine, and has an intermittent rotary or step-by-step motion imparted to it by means of a ratchet-wheel, A², which is fixed upon the shaft A', and a pawl-rod, A³, engaging therewith, and actuated by an eccentric, A⁴, on the driving-shaft C. The ratchet-wheel A² has its teeth corresponding in number with the number of notches a in the wheel A, and the throw of the eccentric A⁴ is such that the wheel is advanced at each step just the distance between two of its notches. In the periphery of the wheel A, adjacent to the notches a , are recesses, in which are fitted sliding dogs b, as seen in Fig. 3, and these dogs are impelled into the notches a by springs b', when not otherwise acted on, to cause their points to bite into the wood blanks and hold them in the notches against turning.

The material from which the bobbins are cut is in the form of a round stick, and it is fed into the notches as they come to the lower side of the wheel in a direction parallel with the shaft A'. The stick of wood is fed into the wheel A between rollers c, by which it is guided, and against a stop, c', (shown in Fig. 1,) which may consist simply of a screw which can be adjusted to allow the stick to be fed through the wheel more or less. As each dog b reaches the position where the stick is fed in

a projection, b², upon it strikes against a stop, b³, which consists of one arm of a bell-crank lever, and the dog is moved back against the force of the spring b' sufficiently to allow the stick to enter the adjacent notch. A rod, b⁴, which is worked by the eccentric b⁵ on the driving-shaft C, is connected to the other arm of the bell-crank stop b³, and before the wheel A is moved forward the stop is moved away from the dog by the eccentric-rod b⁴ and eccentric b⁵, and the dog is moved forward by its spring to cause its teeth to embed themselves in the blank. The rollers c, or one of them, may be positively rotated by a belt, o, and others will feed in the sticks automatically.

Adjacent to the stick as it is fed in is a swing-saw, d, and a mandrel, d', which is sup-

ported in a swinging frame, d^2 , as clearly seen in Fig. 2. The saw is driven by means of a belt, d^3 , passing from a pulley, d^4 , on the driving-shaft to a pulley concentric with the pivot 5 of the frame d^2 and a second belt, d^5 , leading therefrom to a pulley on the said mandrel. The swinging frame d^2 is connected by a rod, d^6 , with an eccentric, d^7 , on the driving-shaft C, and while the wheel A is still stationary, after

10 the stick is fed in the frame d^2 is swung transversely, to cause the saw d to cut off the stick.

Arranged on opposite sides of the wheel A and parallel with its shaft A' are two small spindles, $e e'$, mounted in bearings, in which 15 they may be moved longitudinally, and having cutter-heads e^2 at their ends, which are in proximity to the wheel. In the cutter-heads e^2 are secured knives or cutters of ordinary form, such as are commonly employed to turn the 20 journals or pivots on the ends of wood bobbins. The spindle e is arranged in advance of the spindle e' .

In proximity to the wheel A, and in line with the spindles $e e'$, are stops, rests, or abutments $f f'$, which are in proximity to the ends 25 of the bobbin-blanks when the wheel A is stationary.

D D' designate two shafts, which are parallel with the spindles $e e'$, and which derive 30 their motion from the main driving-shaft C through transverse shafts E E' and bevel-gearing $g g'$ and $h h'$. (Clearly shown in Fig. 1.) The shafts D D' are rotated at the same speed as the driving-shaft C. Upon the shafts D D' 35 are cams F F', which actuate pivoted levers G G', that bear upon the outer ends of the spindles $e e'$, and by these cams and levers the spindles $e e'$ are moved longitudinally toward the wheel A, to cause their cutters to turn journals or 40 pivots on the ends of the bobbins, the bobbins being held against longitudinal movement by the stops, rests, or abutments $f f'$, and against turning by the dogs b in the wheel A. The end of the pivot formed on the bobbin by the 45 cutters on the spindle e does not touch the rest or abutment f' when it comes opposite it, but said rest or abutment is shouldered, so that the shoulder on the bobbin will be pressed against it by a very slight longitudinal movement 50 of the bobbin produced by the spindle e' , while the pivot on the bobbin will move clear of said rest or abutment. The rests $f f'$ may be adjusted by screws s . The cutters of the spindle e act first on one end of the bobbin-blank, 55 pressing it against the stop or abutment f , and the cutters of the spindle e' then act upon the opposite end of the bobbin, pressing it against the stop or abutment f' . The levers G G' are actuated by the cams F F' to move the spindles $e e'$ toward the wheel, and are actuated in 60 the other direction by springs g^2 , as seen in Fig. 1. The spindles $e e'$ are driven by belts e^3 , which may extend from an overhead counter-shaft. (Not here shown.)

65 On the opposite side of the wheel A from the spindles $e e'$ is arranged a pusher shaft or

rod, i , which is adapted to be moved longitudinally in its bearings by a pivoted lever, i' , and a cam, i^2 , on the driving-shaft C. On the opposite side of the wheel A, and in line with 70 the pusher shaft or rod i , is a small shaft, j , carrying a clutch-piece, j' , fast upon it; and j^2 designates a companion clutch-piece which is fixed to or formed with a sleeve, j^3 , as best seen in Fig. 4. The sleeve j^3 is adapted to 75 rotate in a bearing, j^4 , and motion is imparted to it and the clutch-piece j^2 by a belt, j^5 , extending from a pulley, j^6 , on the driving-shaft. The shaft j is adapted to slide longitudinally in the sleeve j^3 to move the clutch-piece j' into engagement with the rotary clutch-piece j^2 , and it is pressed back to disengage the two clutch-pieces by a spring, j^7 , arranged as shown in Fig. 4.

From the shaft j is suspended a weight, j^8 , 85 which tends to draw the shaft in a direction to move the clutch-piece j' into engagement with the rotary clutch-piece j^2 ; but the spring j^7 is more than sufficient to counterbalance this weight, and therefore the shaft j will always 90 be moved toward the wheel A when not otherwise acted upon, but its return will be somewhat retarded by the action of the weight.

Adjacent to the shaft j is a cutter-head, k , 95 which is provided with suitable knives or cutters, and is rotated by a belt, k' , from a pulley, k^2 , on the driving-shaft C. The knives or cutters in the head k are shaped so as to turn the periphery of the bobbin concavely from end to end to receive the thread, and opposite to it or side by side with it is arranged a sand-roll, l , 100 which conforms in shape with the finished bobbin, and is adapted to smooth the bobbin as it is turned by being rotated in a contrary direction to that in which the bobbin is rotated. The sand or smoothing roll may be rotated by a belt from an overhead counter-shaft in a well-understood manner. As the bobbins in the notches of the wheel A are brought into line with the pusher rod or spindle i and the shaft j the projections b^2 on the dogs b come into contact with a pivoted stop, m , which is actuated by an eccentric-rod, m' , and eccentric m^2 on the driving-shaft C, and the dogs are pushed back, so as to release the bobbins held by them. 110 The pusher rod or spindle i then moves toward the wheel A and pushes the bobbin against the end of the shaft j , and the further movement of the pusher-rod carries the bobbin into position to be acted on by the cutter-head k and 115 the sand-roll l , and also carries the clutch-piece j' into engagement with the rotary clutch-piece j^2 , thus causing the bobbin to be rapidly rotated. If desirable, the cutter-head k might be stationary instead of rotary so long as the 120 bobbin is rotated. After the bobbin is finished the pusher-rod or spindle i moves back quickly, but as the shaft j is retarded by the weight j^8 it does not move as quickly, and the pusher rod or spindle i moves away from it, thus allowing the finished bobbin to drop into a suitable receptacle. 125

It will be seen from the above that at each stoppage of the wheel A a bobbin is being cut off by the saw, the opposite ends of two bobbins are having journals or pivots turned on them, and another bobbin is being turned on the periphery.

If the machine is to be employed for making spools, the spindles *e e'*, instead of carrying cutters, should carry drills or bits for boring the spools; and if the machine is to be used for making bungs, the spindles *e e'* and the mechanism for operating them are entirely dispensed with.

By my invention I provide a simple machine which requires no attention save to feed in the long sticks of wood, and which is capable of working very rapidly, having a capacity of thirty thousand to forty thousand bobbins or spools per day of ten hours, and only requiring one attendant to two or three machines.

What I claim as my invention, and desire to secure by Letters Patent, is—

1. The combination, with the wheel having holders in its periphery, and having a step-by-step rotary motion, and dogs for holding blanks in the holders, of two pivoted stops and mechanism for moving them to obtrude them in the path of said dogs to move the dogs, first to permit of the insertion of the stick in the holders and subsequently to release the blanks and to move the stops out of the way of said dogs, substantially as specified.

2. The combination, with the wheel having holders in its periphery, and having a step-by-step rotary motion imparted to it, of a longitudinally-inovable shaft on one side of said wheel, a pusher-shaft on the other side of said wheel, adapted to move longitudinally and push the bobbins or other articles from the wheel and against the opposite shaft, and by its further movement to move the said shaft longitudinally, and a cutter-head, opposite to which the bobbins or other articles are carried

by the two said shafts, substantially as specified.

3. The combination of the wheel A, having holders in its periphery, and having a step-by-step rotary motion, the pusher-shaft *i* and shaft *j*, arranged on opposite sides of said wheel in line with each other, the fixed clutch-piece *j'*, and the rotary clutch-piece *j''*, for rotating the shaft *j*, the sleeve *j³*, surrounding the shaft *j*, the spring *j'*, and the cutter-head *k*, substantially as specified.

4. The combination of the wheel A, having holders in its periphery, and having a step-by-step rotary motion, the spindles *e e'*, arranged one in advance of the other, the stationary rests or abutments *f f'*, the pusher-shaft *i* and shaft *j*, arranged in line on opposite sides of said wheel, and both longitudinally movable, and the cutter *k*, substantially as specified.

5. The combination, with the wheel A, having holders in its periphery, and having a step-by-step rotary motion, the pusher-shaft *i*, and the longitudinally-movable shaft *j*, arranged in line with said pusher-shaft, of a cutter-head, and a sand or smoothing roll, between which the bobbins are carried and rotated by said pusher-shaft and shaft, substantially as specified.

6. The combination, with the wheel A, having holders in its periphery, and having a step-by-step rotary motion, of the rollers *c*, between which the sticks are fed into said wheel, the adjustable stop *c'*, the spindles *e e'*, arranged one in advance of the other on opposite sides of said wheel, and the adjustable stationary rests or abutments *f f'*, all substantially as specified.

HENRY R. SILLMAN.
